UNITED STATES PATENT OFFICE.

JOHN H. BARTELS, OF ST. LOUIS, MISSOURI.

STEAM CONDENSER.

1,420,402.

Specification of Letters Patent. Patented June 20, 1922.

Application filed April 8, 1921. Serial No. 459,625.

To all whom it may concern:

Be it known that I, JOHN H. BARTELS, a citizen of the United States, and resident of St. Louis, Missouri, have invented certain new and useful Improvements in a Steam Condenser, of which the following is a specification.

This invention relates to improvements in a steam condenser, and has for its object a housing constructed of elongated and conical fashion with a water receiving trough located at the apex. The interior of the housing is divided into several compartments by partitions formed of several sections arranged in step-like fashion, and spaced apart thus forming passage-ways in the partition through which the steam may pass and from each partition the condensation may drop to the bottom of the housing and said condensation is permitted to flow along the bottom of the housing and out near the opposite end from which the exhaust steam is admitted.

This structure is conveniently located on the roof of some structure and the housing is suitably cooled by means of running water fed into the trough and permitted to trickle over the outside of the condenser.

Figure 1, is a central sectional view of my improved condenser.

Fig. 2, is the admission end of the same.

Fig. 3, is a cross sectional view taken on the line 3—3 of Fig. 1.

Fig. 4, is a cross sectional view taken on the line 4—4 of Fig. 1.

Fig. 5, is an opposite end view with the upper portion broken away.

Fig. 6, is an enlarged detail sectional view of the admission end showing the inlet pipe.

Fig. 7, is an enlarged detail sectional view of a portion of the opposite end showing the opening by which ingress may be had to the interior.

Fig. 8, is a perspective view of my invention with a part broken away showing the internal construction.

Fig. 9, is a detail perspective view of one of the members forming the partition.

Fig. 10, is a detail perspective view of the lower section of the partitions.

Fig. 11, is an enlarged detail sectional view of the upper portion of the housing showing the trough and the water feed.

Fig. 12, is a top plan view of a portion of the condenser.

In the construction of my invention I provide a condenser consisting of a housing preferably built up of sheets of durable material and properly riveted together, the same being of any desirable length but preferably shaped in conical form in cross-section as that illustrated in Figs. 2, 3, and 4. This housing consists of a curved bottom 13 and two slanted walls 14, and at the apex 15 it is provided with a trough 16 which is preferably in the form of an angle bar with the ends closed, and to this angle bar is rigidly attached the upper ends of the walls 14 of the housing.

To the one end 17 of the housing is attached the steam inlet pipe 18, the same being held in position by the flanged connection 19 and from this pipe the exhaust steam is admitted into the interior of the housing. The opposite end 20 of the housing is provided with a suitable opening 21 which acts as a man-hole through which ingress may be had to the interior of the housing so that a workman may enter into the same when it becomes necessary for general repairs or for cleansing purposes. This opening is normally closed by means of a plate 22 held in position by bolts or other suitable means so that the plate can be readily removed and re-placed when so desired.

The interior of the housing is divided into a plurality of compartments, this is done by placing in the housing a number of partitions A, B, C, D, and E. Each of these partitions is formed of a number of sections and they are built up and placed in position within the housing at an angle with the bottom of the housing as illustrated in Fig. 1. The lower section of each partition is shaped to fit the bottom of the housing and the same is provided with a notch forming a passage-way 24 through which the condensation in the bottom of the housing is permitted to pass and drain out of the housing through the discharge opening 25. These base sections are provided with flanges 26 by which said sections are bolted to the housing and the un-flanged extension of this section is rigidly held in position by means of lugs 27 attached to the interior of the housing. The purpose of attaching the lower sections to the housing by means of bolts is that when it is desired to enter the housing by way of the man-hole for cleansing or repairing the same, the nuts from the bolts can be

removed and the lower sections, one after the other, removed so that the workman can pass from one compartment to the other.

The remaining sections which compose the

- 5 partitions are constructed in the manner shown in Fig. 9, each section consisting of a plate 28 with side flanges 29, the sides being so shaped as to fit the housing and they are firmly riveted in position one against the 10 other. The flanges 29 space the sections apart so as to form passages 30 between the sections through which the steam may pass from one compartment to the other.

The partition A is preferably built up of 15 four sections and located higher in the housing than the section B, thereby as the steam enters the first compartment in front of the partition A, the steam passes through the passages 30 and through the small passage 20 31 formed above the partition A. As the steam strikes the partition a certain amount of condensation takes place, the steam then passes on and strikes the partition B, the opening 32 at the top being larger allows for 25 the passage of the expanded steam, and as it strikes this partition a certain amount of condensation takes place, and so on, the steam passes from one compartment to the other until it reaches partition E, when virtually all of the steam has been condensed 30 and the vapor is permitted to pass out through the vent opening 33 formed in the end 20 of the housing.

Water is fed into the trough 16 by means 35 of a water supply pipe 34 and when the water fills the trough it overflows and contacts with the entire outer surface of the housing, the manner of overflow being illustrated in Fig. 11. This water has a tendency 40 to keep the condenser cool so that when the hot steam is directed into the housing a rapid condensation takes place, and this overflow water is permitted to enter into a container built below the condenser and the 45 condensation from the condenser can be directed to any suitable source where said condensation can be re-used.

Having fully described my invention what I claim is:

- 50 1. A steam condenser comprising an elongated conical shaped housing, end walls clos-

ing the same, a trough located at the apex of the housing and a plurality of partitions formed of overlapping flanged sections located at intervals within said housing, substantially as specified. 55

2. A steam condenser comprising a housing, a steam inlet connected to one end, a man-hole formed in the opposite end, a plurality of partitions located in said housing, each partition comprising a set of flanged sections spaced apart and arranged at an angle with the bottom of the housing and between which the exhaust steam must pass and a notch formed in the bottom of 60 each partition for the flow of the condensation, substantially as specified.

3. A steam condenser of the class described comprising an elongated conical shaped housing, a top formed at the apex 70 of said housing, partitions located in said housing and spaced at intervals apart, each partition consisting of a number of sections, each arranged at an angle with the bottom of the housing and spaced apart forming 75 passages between the sections, the lower section having its bottom provided with a notch for the passage of the condensation, said section detachably secured to the housing so that ingress may be had to the several compartments formed by the partitions, substantially as specified. 80

4. A steam condenser comprising a conical shaped housing, a top at the apex thereof, a steam inlet at one end of said housing, 85 means for permitting ingress to the interior of the housing, partitions located in the housing and dividing the interior into several compartments, each partition consisting of a number of flanged sections arranged 90 one against the other forming passages between the sections, said sections arranged at an angle with the bottom of the housing, and in step-like fashion, substantially as specified. 95

In testimony whereof, I have signed my name to this specification, in presence of two subscribing witnesses.
